Inventor:

Frank P. Whitaker,
by Charles E. Tulla
His Attorney.

UNITED STATES PATENT OFFICE

FRANK P. WHITAKER, OF RUGBY, ENGLAND, ASSIGNOR TO GENERAL ELECTRIC COMPANY, A CORPORATION OF NEW YORK

MERCURY-ARC RECTIFIER

Application filed June 17, 1929, Serial No. 371,575, and in Great Britain June 20, 1928.

My invention relates to mercury arc rectifiers and the like, and more particularly to apparatus for the prevention of arc-backs in such rectifiers.

5 The invention consists in providing an anode of approximately inverted pear shape, the anode being provided with an insulated anode shield secured above its upper or larger end, and extending downwards a considerable distance below its point or lower end. In close proximity to the anode and within the shield is mounted a series of truncated cone shaped baffles, which are supported from the anode shield. With such an arrangement the tendency to arc-back is reduced.

In the accompanying drawing illustrating a typical form of my invention, Fig. 1 is an elevational view partially in section and Fig. 20 2 is a horizontal section taken on line 2—2 of Fig. 1.

In the drawing, 1 is the anode, of inverted pear shape, which is introduced through the wall of the vacuum chamber of the rectifier 25 through the insulator 2. 3 is the anode shield, of approximately cylindrical shape, which may be carried on the insulator 2 and which surrounds the wide end of the anode closely. Access for the arc to the tapered 30 portion of the anode face is given through the spaces between the sheet metal baffles 4 which have the shape of upright truncated cones. The apex angle of the cone shaped surfaces is chosen of such value that the baffles 35 are substantially perpendicular to the anode surface. A plate 5 prevents the direct access of the arc to the point of the anode. Radial metal plates 6 support 4 and 5 from the anode shield 3.

40 The best proportions are determined by experiment in any given case, but generally the distance from the anode surface to the truncated cones, and the distance between adjacent cones, are both approximately of the order of an inch.

What I claim as new and desire to secure by Letters Patent of the United States is:

1. In a mercury arc rectifier, an inverted pear shaped anode, a cylindrical shield arranged to surround said anode, and a plural-

ity of truncated cone shaped baffles spaced from each other and arranged within said shield to surround said anode.

2. In a mercury arc rectifier, an anode provided with a tapered arc receiving surface, a 55 shield arranged to surround said anode, and a plurality of truncated cone shaped baffles arranged within said shield and surrounding said surface, said baffles being substantially equally spaced from each other and 60 from said surface.

3. In a mercury arc rectifier, an anode provided with a tapered arc receiving surface, a shield arranged to surround said anode, and a plurality of truncated cone shaped baffles 65 within said shield arranged to surround said surface and extend substantially perpendicular thereto.

In witness whereof, I have hereunto set my hand this 24th day of May, 1929.

FRANK P. WHITAKER.
